Attorney

UNITED STATES PATENT OFFICE.

EZRA DIXON, OF BRISTOL, RHODE ISLAND.

WEIGHT HOOK.

Application filed June 20, 1924. Serial No. 721,344.

To all whom it may concern:

Be it known that I, EZRA DIXON, a citizen of the United States, residing at Bristol, in the county of Bristol and State of Rhode Island, have invented new and useful Improvements in Weight Hooks, of which the following is a specification.

This invention relates to certain new and useful improvements in weight hooks and 10 pertains more especially to the hook employed for supporting the weights that bear upon the rolls ordinarily used in connection with twist and winding machines.

The primary object of the invention is to 15 provide a weight hook structure which has novel means for adjusting same so as to bring the weight directly beneath the roll or at a distance therefrom depending upon the bearing that is required between the 20 rolls.

A further object of the invention is to 25 provide simple and economical adjusting means for attaining the afore-mentioned object which is capable of easy and quick adjustment and which is readily accessible for purpose of such adjustment.

The invention has still further and other objects which will be later set forth and manifested in the course of the following 30 description.

In the drawings;

Figure 1, is a side elevation of the invention, partly broken away and in section showing the device in solid lines in initial 35 position when placed on the roll and showing in dotted lines normal operative position thereof:

Figure 2, is a top plan view:

Figure 3, is a front elevation, and

Figure 4, is a section on line 4-4 of 40 Figure 1.

In proceeding in accordance with the present invention a saddle is employed which consists of a body 1, concaved at 2 45 to seat on the upper arc of a roll 3. A curved finger piece 4 extends outwardly from one end of the body 1 and is provided for the purpose of lifting the weight up from the roll, when desired or found necessary.

The body is formed with an oil receiving 50 chamber 5 which at its bottom is formed with constricted oil outlets 6. A U-shaped wick 7 is arranged in the outlets 6 so as to feed oil by capillary attraction to the roll

3. The finger piece 4 is located on one side of the oil chamber while the opposite side is flanked by an enlargement 8 which extends for a distance above the top of the oil chamber and is formed with a threaded opening 9 in which is threadedly received a screw 10. The inner end of the screw projects beyond the inner end of the enlargement 8 and is provided with a screw-driver receiving slot 11, while the outer or front 60 end of the screw is provided with a pair of spaced disks 12 and 13 of which 12 is of less diameter than 13 and is located inwardly of the latter.

The weight hook consists of a metal strap 70 14 having a hook 15 at its lower end by means of which the eye 16 of the weight 17 is attached thereto, while its upper end is formed with a key-hole slot 18, the disk 12 being movable through the large end 75 of the slot.

From the foregoing it will be apparent 80 that the screw may be inserted at its free end through the enlarged end of slot 18 and the strap then moved to lie in the space 85 between the two disks 12 and 13. The screw may be easily and quickly adjusted by use of a screw driver so as to vary the position of the strap 14 to thus bring the weight 4 directly beneath the roll or at a distance 90 therefrom in accordance with the required bearing between the rolls. The weight of the parts hold the screw against accidental rotation and the latter can be easily and economically replaced upon wear or breakage.

Having thus described my invention, what I claim as new and desire to secure by Letters Patent is:-

1. In a device of the type set forth, a 95 body formed to seat on a roll and having a finger piece at one end and an enlargement at its opposite end, an oil chamber between the finger piece and enlargement and the enlargement having a threaded opening disposed above the finger piece and oil chamber, a strap having a weight at one end and a key-hole slot in its opposite end, and a screw having a pair of vari-dialed and spaced disks on one end the smaller of which 100 is movable through the enlarged part of the key-hole slot so as to dispose the strap in the space between the disks, the inner end of the screw having a screw driver receiving slot.

2. In combination with a top roll saddle having a roll-engaging seat between its ends, a weight-carrying hook disposed wholly beyond an end of said saddle, and 5 means to connect the hook to said end of the saddle so as to cause the weight to lie beneath the roll and in the vertical plane in which the roll lies.

3. In combination with a top roll saddle, a screw carried by the saddle and having a pair of vari-diametered and spaced disks, and a strap having a weight at one end and an opening at its opposite end, said opening being of a size to receive only the 10 smaller diametered disk therethrough, said smaller diametered disk being disposed adjacent to the saddle whereby to hold the 15

strap against removal from the screw without removal of the screw from the saddle.

4. In combination with a top roll saddle 20 having a roll-engaging seat between its ends and having a finger extending outwardly from one end thereof, a screw extended outwardly from the opposite end of the saddle, and a weight-carrying hook connected to the screw and disposed wholly beyond 25 said end of the saddle.

In testimony whereof I have signed my name to this specification in the presence of two subscribing witnesses.

EZRA DIXON.
